OIL ACCUMULATION DRAIN MEANS FOR
RADIAL ENGINES

Carl G. A. Rosen, Peoria, Ill., assignor to Caterpillar Tractor Co., San Leandro, Calif., a corporation of California

Application February 7, 1944, Serial No. 521,327

4 Claims. (Cl. 123—55)

1

My invention relates to internal combustion engines, and more particularly to an internal combustion engine having inverted cylinders, such as a radial engine.

In such type of engine, a liquid such as lubricating oil is very apt to flow from the crankcase of the engine, when the engine is not running, into an inverted cylinder, and seep past the piston. Such liquid may accumulate between the piston crown and the cylinder head, which might result in breakage when the engine is started because the piston may strike the accumulated pool of liquid, causing transmission of extremely high pressure to both the piston and the head of the cylinder. This problem may be extremely aggravating in a compression ignition or Diesel engine by virtue of the relatively slight clearance which is generally provided between the crown of the piston and the piston head, to provide for the relatively high compression under which a compression ignition engine generally operates.

My invention is designed to obviate this problem, and has as its objects, among others, the provision of improved mechanism enabling opening of a valve for allowing drainage of liquid from the cylinder; which may be automatically actuated to open such valve when the engine is shut off; and which is of relatively simple and economical construction. Other objects of my invention will become apparent from a perusal of the following description thereof.

Referring to the drawings:

Fig. 1 is a fragmentary and partially schematic vertical sectional view, transverse to the crankshaft axis, of a form of radial internal combustion engine embodying engine valve opening mechanism of my invention.

Fig. 2 is a plan view, taken in a plane indicated by the line 2—2 in Fig. 1 of the control linkage embodied in the arrangement of my invention; a portion of the structure being shown in section to illustrate more clearly the construction. Portions of engine control mechanism, not shown in Fig. 1, appear schematically in Fig. 2.

Fig. 3 is a section taken in a plane indicated by line 3—3 in Fig. 1.

Fig. 4 is an enlarged vertical sectional view, taken in planes indicated by line 4—4 in Fig. 1, of a portion of the construction illustrated in Fig. 1.

Fig. 5 is a developed schematic view of the mechanism including the cam for opening the engine valve.

The engine illustrated is a radial Diesel or

2

compression ignition engine of the type shown and described in my assignee's patent to Lloyd E. Johnson and Carl R. Maxwell, Patent No. 2,398,182, dated April 9, 1946, for "Internal combustion engine." However, it is to be understood that the arrangement of my invention may be employed in any other type of engine having an inverted cylinder in which liquid, such as lubricating oil, is apt to accumulate. With reference to Fig. 1, the engine comprises a crankcase 2 having a plurality of peripherally or circumferentially disposed cylinders 3, and heads 4 over the cylinders; the cylinders and heads being preferably of the air cooled type, having cooling fins 6. Connected to crankshaft 7 journalled in crankcase 2, is a master connecting rod 8 connected in turn to one of pistons 9 in one of the cylinders 3; auxiliary connecting rods 11 being connected to the remaining pistons 9.

20 In the head 4 of each cylinder are located the usual axially reciprocatable spring loaded inlet valve 12 and exhaust valve 13 which control cylinder gas flow in the usual manner; the stem 14 of each of which is axially slidable in a sleeve 16. Head 17 of each of such valves is adapted to seat against seat insert 18 in the closed position of the valve. A plurality of coil springs 19 about each valve stem 14, and abutting a spring retainer 21, of any suitable construction, mounted on such stem, serve to urge the valve toward seated position. Opening of each valve is effected in the well-known manner by means of tappet mechanism including axially reciprocatable tappet rod 22; the inner end 25 of which is actuated from the camshaft of the engine in the manner illustrated in the previously mentioned copending application.

The outer end of each tappet rod 22 is connected by a ball and socket joint 23 to one end of the usual rocker arm 24 journalled for pivotal movement about a pin or shaft 25, and which has a roller 26 journalled on the end over valve stem 14 to engage the same. Each tappet rod 22 is housed in an elongated sleeve structure 27, a portion of which is illustrated in Fig. 4, and which includes adjacent parts held together adjacent cylinder head 4 by means of resilient clamping structure 28. From the preceding, it is seen that the tappet mechanism actuates each engine valve to open position; while the spring means 19 returns the valve to closed position in a well-known manner.

With respect to compression ignition engines in which the arrangement of my invention is employed, the engine is generally governor con-

trolled, and fuel is supplied to the engine by fuel injection pumps (not shown) which are automatically adjusted by any suitable governor mechanism 31 indicated in Fig. 2. The quantity of fuel which such injection pumps may supply the engine to thus control the speed of the engine is controlled by the governor in a well-known manner, as determined by the usual setting of throttle control linkage 32 connected to the governor, and including manually settable throttle control lever 33. Governor 31 is connected to the fuel injection pumps to actuate the same, by means including rod 34 pivotally connected to lever 36 having adjacent one end thereof an integral arm portion 37.

To stop or shut off the engine while it is operating, the usual engine shutoff control mechanism is provided. Such mechanism, includes a linkage comprising pivoted lever 38 having an arm 39 which, when moved in a clockwise direction with reference to Fig. 2, is adapted to engage arm 37 to move rod 34 in a direction for shutting off the pumps, and thus stop the engine. Lever 38 is pivotally connected to link 41 in turn pivotally connected to pivotally mounted bellcrank 42 which is also pivotally connected to rod 43 having a pivotal connection at 44 with bracket plate 46 fixedly secured to a tubular rod 47 which forms part of the engine valve opening mechanism of my invention in a manner to be subsequently described. As is indicated in Fig. 2, tubular rod 47 is connected to manually manipulatable engine shutoff control lever 48.

When shutoff control lever 48 is moved in a direction to move rod 47 upwardly with reference to Fig. 2, as is indicated by the direction arrow in Fig. 2, arm 39 will engage arm 37 to shut off the engine in the manner previously described. When the shutoff control lever is moved in the opposite direction, arm 39 will be moved out of the way of arm 37 to allow the speed of the engine to be controlled by the governor in the manner previously related, as determined by the setting of throttle control lever 33. Thus, it is seen that shutoff control lever 48 has two positions; namely, the shutoff position determining shutting off of the engine, and the engine running position at which the shutoff control lever permits functioning of the governor.

When the engine is not running, liquid, such as lubricating oil, may drain from crankcase 2 into the lowermost adjacent cylinders 3 illustrated in Fig. 1. Such oil may seep past pistons 9 in such cylinders and accumulate between the piston crowns and the cylinder heads, and thus cause the possible damage when the engine is started after being idle for some time, as was previously related. To overcome this danger, I provide mechanism for opening one of the engine valves in each of lowermost cylinders 3, to permit drainage of liquid from such cylinders, and thus obviate accumulation of oil therein.

Associated with each of inlet valve 12 of one of such cylinders and with exhaust valve 13 of the other cylinder adjacent thereto, (these valves being in the lowermost parts of the respective cylinders) is a cam member 51. Each of cam members 51 has a stem 52 journaled for turning movement in a bushing 53 screwed in a cover member 54 detachably secured to the associated cylinder head, by cap screws 55. Such stem 52 is axially aligned with stem 14 of the associated engine valve, so as to extend in the direction of the axis of reciprocation of stem 14. On the inner end of each stem 52 is fixed a cam 56 hav-

ing a cam face 57 extending transversely with respect to the axis of reciprocation of the associated valve, and which is adapted to engage rocker arm roller 26. The opposite or outer end 58 of cam stem 52 extends beyond bushing 53 and has secured thereto a linkage to be subsequently described, for enabling turning of the stem, and consequent turning of cam face 57. A seal 59 of suitable material, such as rubber, is provided in the periphery of bushing 53; and another seal 60 is located in an end recess in such bushing, about stem 52.

Cam face 57 has a dwell portion 61, a ramp portion 62, and a peak or nose portion 63. When stem 52 is turned to move nose portion 63 adjacent rocker arm roller 26, the associated valve will be lifted, so as to cause opening of such valve, and thus allow oil to drain from the associated cylinder. The drained oil will seep into a passage 65 below the inlet valve, and into a passage 65' below the exhaust valve, which communicate, respectively, with the intake and exhaust manifolds (not shown). Thus, any drained oil in inlet passage 65 will be consumed by the engine during operation thereof; and any drained oil in the exhaust passage 65' will pass out with the exhaust gases during running of the engine.

In the inactive position of cam 56 which obtains while the engine is running, stem 52 is so turned that dwell portion 61 is free of engagement with roller 26 in the seated position of the associated engine valve, so as not to interfere with the normal operation of such valve. This is indicated in Fig. 5, which illustrates the right-hand position of roller 26 out of contact with dwell portion 61.

So that cam 56 may have its cam face 57 in proper spaced relationship with respect to rocker arm roller 26 and valve stem 14, bushing 53 is screwed in cover member 54 a predetermined extent, as determined by washer 64 of predetermined thickness, against which a peripherally notched flange 66 on bushing 53 is adapted to abut. Notches 67 in flange 66 enable bushing 53 to be held against rotation and thus maintained in proper position, by means of a capscrew 68, having a head 69 adapted to be received in one of notches 67; such screw being secured in cover member 54. To hold the screw against turning, a cotter pin 71 is provided in its head 69, and engages the periphery of flange 66. In the embodiment of the invention illustrated, cover member 54 is of aluminum. Consequently, the threads between cover member 54 and bushing 53 might wear resulting in play, with consequent disturbance of the proper position of cam 56. However, this is precluded by having the washer 64 of a hard metal, such as steel, to thus provide a firm base against which flange 66 of bushing 53 may be cinched.

Actuating means is provided to open automatically engine valves 12 and 13 when after operation of the engine, the engine is shut off by movement of fuel shutoff control lever 49 to the shutoff position. Also, such means permits these valves to assume their normal operating position when fuel shutoff control lever 49 is moved from shutoff position to open position for operation of the engine. Fixed in proper position to the end portion 58 of each cam stem 52, is an arm 81 having a split hub 82 clamped to such stem portion 58, by means of a capscrew 83; the hub being secured in proper position by key 84. As can be seen more clearly from Fig. 2, arms 81 extend in opposite directions from the stem portions 58, and are

pivotedly connected by means of a link member 86. The direction of turning of arms 81 for lifting valves 12 and 13 is indicated by the direction arrows in Fig. 2; and in this connection, it is to be noted that one of the arms 81 is provided with a stop portion 87 adapted to engage a fixed stop 88 on cover member 54 for fixing the maximum lift of the valves when they are opened.

The left-hand arm 81 with reference to Figs. 1 and 2, is provided with a wing extension 89 pivotedly connected to a rod member 91 extending into tubular rod 47 which is connected to shutoff control lever 49 in the manner previously described. Rod 91 has fixed therein a cross member 92, the ends of which engage in diametrically opposite elongated slots 93 in tubular sleeve 47; and a spring 94 about rod 47 is compressed between a spring retainer 96 held against cross member 92, and a spring retainer 97 held against the lower end of rod 47. By this arrangement, when rod 47 is moved upwardly with reference to Fig. 2, as indicated by the direction arrow, to shut off the engine, rod 91 will also be moved in the same direction through spring 94, to open valves 12 and 13. Closing of the valves after they have been opened, will be automatically effected in a reverse manner when the fuel shutoff control lever 49 is moved from engine shutoff to engine operating position.

It may be that one of the cylinders containing valves 12 and 13 might be under compression at the moment control lever 49 is moved to shut off the engine during running thereof. Should this occur, damage might result because of the counter-pressure which would be exerted against the valve by the gases in the cylinder under compression. However, should this condition actually exist, it will be noted that spring 94 can yield; and it will store up sufficient energy to effect opening of valves 12 and 13 with a delayed action as soon as the pressure in the cylinder under compression, has dropped to the point permitting opening of the valves. Thus, the described connection in the linkage for opening the valves serves as a yieldable spring loaded actuating connection to insure that no damage will occur should one attempt to shut down the engine just at the time when one of the cylinders in question is under compression.

I claim:

1. An internal combustion engine comprising an inverted cylinder in which liquid is apt to accumulate between a piston in the cylinder and a head over the cylinder, an engine valve associated with the cylinder, a control member for shutting off the engine, and mechanism con-

nected to the member for opening the valve when the control member is moved to shut off position to allow drainage of liquid from the cylinder, the mechanism including yieldable actuating means for delaying opening of the valve until compression in the cylinder is relieved should the control member be moved to shut off position when the cylinder is under compression.

2. An internal combustion engine comprising a cylinder in which liquid is apt to accumulate, a reciprocatable valve for allowing drainage of liquid from the cylinder, a control member for the engine; and mechanism for opening the valve including a cam having a cam face extending transversely with respect to the axis of reciprocation of the valve and which is mounted on a stem extending in the direction of such axis, and linkage connected to the control member and to the stem for turning the stem, the linkage including a spring loaded actuating connection.

3. The combination with a reciprocatable spring loaded engine cylinder valve for controlling cylinder gas flow, and means for actuating the valve when the engine is running, of mechanism for opening the valve comprising a turnable cam having a cam face engageable with such mechanism and which extends transversely with respect to the axis of reciprocation of the valve, the cam being mounted on a stem extending in the direction of such axis, a control member, and linkage connected to the control member and to the cam stem, the cam face having a portion which is adapted to be free of engagement with said mechanism in the seated position of the valve when the engine is running.

4. An internal combustion engine comprising a cylinder in which liquid is apt to accumulate, a valve for allowing drainage of such liquid, a control member for the engine, and mechanism connected to the control member for opening the valve, said mechanism including yieldable means for delaying opening of the valve until compression in the cylinder is relieved should the control member be moved to open the valve when the cylinder is under compression.
